(57) **CLAIM**

The ornamental design for a cup, as shown and described.

DESCRIPTION

FIG. 1 is a front side elevational view of a cup showing my new design;

FIG. 2 is a side elevational view thereof showing the side opposite that shown in FIG. 1;

FIG. 3 is a top plan view thereof; and

FIG. 4 is a left side elevational view thereof, the right side elevational view being a mirror image.
